ELECTRIC TARGET PRACTICE GAME

William P. Falkenberg, Chicago, Ill., assignor to
Rayolite Rifle Range Company, Chicago, Ill.,
a corporation of Oklahoma

Application December 7, 1936, Serial No. 114,668

6 Claims. (Cl. 273—101.1)

My invention relates to improvement in electric target games or devices and has for one purpose the provision of an improved target device in which the user fires flashes of light from a "gun" at a target which has associated therewith a photosensitive element.

Another purpose is the provision of a game in which a moving target is fired at.

Another purpose is the provision of such a game in which the scoring of a hit against the target causes the movement of an indicator member.

Another purpose is the provision of such a game or device in which non-visible light is employed in connection with the circuit.

Another purpose is the provision of improved means for setting the device in readiness for operation in response to the insertion of a coin in a coin-controlled mechanism for limiting the number of shots which can be taken.

Other purposes will appear from time to time in the course of the specification and claims.

I illustrate my invention in the accompanying drawings, wherein:

Figure 1 is a perspective view of the device in use;

Figures 2 and 3 are wiring diagrams;

Figure 4 is a section on an enlarged scale taken on the line 4—4 of Figure 1;

Figure 5 is a section on the line 5—5 of Figure 4;

Figure 6 is a section on the line 6—6 of Figure 4; and

Figure 7 is a section on the line 7—7 of Figure 4.

Like parts are indicated by like symbols throughout the specification and drawings.

Referring to the drawings, 1 generally indicates any suitable cabinet having a base 2, a front panel 3, apertured as at 4, and provided with an enlarged upper opening as at 5 which may be closed with glass or the like if desired. A removable upper panel 6 may be employed, the upper portion of which is provided with a pair of double gates 7, 8, hinged thereto and normally in closed position. 9 indicates any suitable clock face, the lower portion of which depends into the opening 5. 14 indicates an intermediate horizontal partition within the housing which serves as means for supporting some of the structures herein described.

Cooperating with the clock face 9 is the pointer or hand 10 which is mounted on a shaft 11 journaled in any suitable bearings 12 on the bracket 13 mounted on the horizontal partition 14. Referring for example to Figure 3, the pinion 11a is shown as in mesh with a rack 15 having a plurality of gear teeth 16 on its lower edge and a plurality of ratchet teeth 17 on its upper edge. It is normally urged, as by the spring 18, to movement toward the left, referring to the parts in

the position in which they are shown in Figure 3, and such movement is limited by a stop 19. Any suitable top and bottom guides 20, 21 may be employed, the stop 19 being herein indicated as forming part of the lower guide 20. The upper 5 guide 21 is broken away as at 22.

In order to impart movement to the ratchet bar 15, and thus to the pinion 11a and the clock hand 10, I provide the following mechanism. An electro-magnetic coil 23 operates a solenoid bar 24 to which is pivoted the link 25 which in turn is pivoted as at 26 upon the plate or bracket 13. Pivoted to its opposite end is a dog 27 to one end of which is secured the spring 28, the opposite end of the spring being also secured to the plate 13. It will be understood that when the coil 23 is energized through the circuit later described, the result is to move the solenoid bar 24 to the left, which causes a counter-clockwise rotation of the lever 25 which moves the dog 27 into contact with the teeth 17, it being drawn down by the spring 28. Thus each energization of the coil 23 causes a movement of the bar 15 one step to the right, referring to the position of the parts in Figure 3. This causes rotation of the pinion 11a and thus of the hand 10. It will be understood that the coil 23 is energized in response to the scoring of a hit against the photoelectric target which will later be described in detail.

Reset means are also employed for permitting the bar 15 to return to initial position, it normally being held against retrograde movement. I illustrate for example a pivoted detent 28 which has associated therewith an armature 29. The spring 30 normally holds the detent in operative position. Any suitable electromagnetic coil or coils 31 are employed which, when energized, lift the armature 29 and thereby remove the detent 28 from operative position. The result is to permit the spring 18 to move the bar 15 to the initial or full line position in which it is shown 40 in Figure 3.

I illustrate also in connection with the cabinet 1 and the hinged doors 7 and 8, a bird or other suitable signal 35 which is mounted on a slide 36 to the rear of the doors 7 and 8. Any suitable rollers 37 may be employed to render its outward movement easier and guides 38 are employed to guide its movement. It is connected to the doors 7 and 8 as by the pivoted links 39 whereby, when the slide 36 is forced forward, the doors open in front of it to permit the bird to emerge. 40 indicates an actuating link for the slide, it being pivoted as at 41 and normally held in the position in which it is shown in Figure 4, as by the spring 42.

Any suitable means may be employed for actuating it, but I illustrate the solenoid 43 which, when energized, moves the link 40 in counter-clockwise direction and thereby urges the slide 60

36, with the bird upon it, into the open, through the opened doors 7 and 8. The energization of the solenoid will be discussed in connection with the wiring diagram herein employed. It will be understood, however, that when the bar 15 reaches the end of its movement, in the dotted line position of Figure 3, in response to a complete series of hits, an abutment member 44 engages the switch leaf 45 and moves it into closed position against the contact 46 which permits a flow of current from an outside source of electric power to energize the transformer 47 whereby the solenoid 43 is energized. Thus when the rod 15 is moved by an unbroken sequence of hits to the end of its position, it releases the bird 35, as a further indication of the success of the marksman. Any other suitable signal might be employed, visible or audible, for indicating a perfect score, but I find the emergence of the bird 20 a satisfactory solution.

Referring to the target proper, at which the marksman shoots, I illustrate a pendulum arm 50, pivoted as at 51 upon any suitable bracket 52. Secured to the upper portion of the pendulum 50 is a block of insulating material 53 carrying two spring thrust contacts 54, 55 which abut against fixed contact segments 56, 57 mounted upon an insulating block 53a. Any suitable lines 58, 59 extend along the pendulum 50 to the photoelectric cell 60 which is shown as enclosed in a housing 61 having a forward lens 62 in an aperture conforming in size to the lens.

In order to impart oscillation to the pendulum, I provide any suitable motor 63 which, through any suitable gearing device, operates a pinion 64 in mesh with the large gear 65 pivoted on any suitable bracket 66. 67 indicates a link connecting the gears 65 and the pendulum 50 whereby, in response to rotation of the motor, the pendulum 40 is swung through a considerable arc in the open space 5. The pendulum is herein shown in sight all the time so that it could be fired at any point in its movement, referring to the device as shown in Figure 1. It will be understood, however, that 45 any suitable masking means might be employed whereby the pendulum could be shot at only at some part or parts of its arc of movement.

Referring to the general circuit and the general operation of the device I illustrate, in Figure 1, a firing stand generally indicated as 70. The stand may include any suitable gun rack 71 and a coin slide 72 into which a coin may be inserted and which may then be employed to move the coin controlled switch 73 from the position in which it is shown in Figure 2 in full line to the dotted line position. It is normally held in the full line position as by the spring 74 and it returns to that position as soon as the operator releases the coin slide 72. The firing stand 70 is provided 50 with a forward aperture 75 alined with which is the light 76 which may direct a ray or beam of light at a photo cell 77 alined with the aperture 4 of the cabinet 1. It may be enclosed in any suitable housing 78 with a forward aperture and lens 79. 80 generally indicates any suitable gun which may include a trigger switch 81, an opposed contact 82, a light source 83, and a trigger 84.

Referring to the wiring diagram whereby these 70 various parts are employed and tracing first the result of the insertion of a coin and the following actuation of the slide 72, the switch 73 is moved into the dotted line position of Figure 2. The circuit may be traced from one terminal of a 75 suitable source of 110 volt alternating current by

the line 85 to the contact 86, contact 87, line 88, to the voltage reducer 89, herein shown as a lamp, and thence by the line 90 to the reset magnet A. The circuit then extends by the line 91 to the junction 92, and the line 93 over the switch 94 to the opposite terminal 95 of the outside source of power. In other words, when the manual control switch 94 is closed, the result of the insertion of a coin and the closure of the switch 73 is to energize the reset magnet A, which thereupon lifts the detent 96 and permits the spring 97 to move the ratchet 98 from the dotted line to the full line position in which it is shown in Figure 2. Any suitable stop may be provided for limiting the movement of the bar 98 in response to the spring 97. This ratchet bar 98, which is generally similar in its movement to the bar 15 already described, controls the number of shots which can be taken in response to the insertion of a single coin. All the mechanism shown in Figure 2 is enclosed in the gun stand 70.

It will be understood that thereafter, at each shot or at each trigger pull, the solenoid coil 99 is energized causing the link or lever 100 to move in a counterclockwise direction, thereby causing the dog 101 to engage the ratchet teeth 102 and to move the bar 98 to the right. The detent 96, which has been released by the swing back of the switch 73 in response to the spring 74, has already been dropped into detent or holding position and, after each forward step of the bar 98, prevents retrograde movement of the bar. Finally, for example, at the tenth actuation of the solenoid 99, the rack bar 98 moves the switch member 103 from the full line position to the dotted line position of Figure 2 and breaks contact with the fixed contact member 104. The plunger of the solenoid 99 is provided also with an abutment 105 which actuates a multiple switch 106 which is normally held in open position, as by the spring 107. When the solenoid plunger is actuated, in response to a trigger pull, it closes all three of the contacts of the switch 106. This switch 106 should be considered in connection with the switch 103. When the coin controlled switch 73 is closed with a resultant movement of the bar 98 to the full line position of Figure 2, the switch 103 is closed in relation to the fixed contact 104, with the following results. Current flows along the line 85 to the junction 108 and thence to the primary coil of the transformer B, thence by the line 109, 110, 111 to the contact 104, the switch 103 and back to the line 93 to the power line 95. A parallel or shunt connection 112 illuminates the lamp 76. The secondary coil of the transformer B is in circuit with the rectifier C.

When the trigger 84 is pulled it moves the switch 81 against the fixed contact 82 and, the spring 74 having already moved the switch 73 to the full line position, it closes a circuit which may be traced as follows:

The line 114 extends from the positive terminal of the rectifier C, across one switch member 115 and then by the line 116 to the solenoid coil, 99, 65 which actuates the shot counter lever 100, and then by the lines 117, 118, 119, across the gun switch members 81 and 82, and thence by line 120 through the switch 72 and by a line 121, 122 to the negative terminal of the rectifier C. Thus 70 the result of closure of the trigger has been to actuate the shot counter and to move the bar 98 one step, thus using up one of the shots allowed to the operator.

Since the result of the operation of the solenoid 75

99 is to close the triple switch 106, a holding circuit is established through the line 123 from the line 118 across the switch member 106a, to the line 122. Thus when the switch 81 again opens, current is still permitted to flow through the solenoid coil 99 as long as the member 106a is closed, which is for an additional fraction of a second. A circuit is also closed through the line 124 which extends in parallel from 114 to 118 and includes the slow acting electro-magnet 125 which when energized, eventually breaks the double switch members 115 and 115a.

Actuation of the switch 106 also causes a flow of current from the main line 85, thence from the junction 126 and the line 127 to the primary coil of the transformer D, thence by the line 128 across the switch member 115a, and by the line 129, the switch member 106c, by 130, 131, thence to 110, 111, 104, 103 and back to the line 93 to the terminal 95. This energizes the transformer D, the secondary coil of which is connected by the lines 132, 133 to the light 83. This causes the light to flash on and permits the gun to direct a flash of light in response to the trigger pull, the path of the light flash being indicated as at 134. After the light 83 is flashed on, slow acting magnet 125 acts and breaks the switch members 115 and 115a, which has for effect to de-energize the solenoid 99 and to break the connection for the gun lamp transformer D. The action of the magnet 125 is so timed as to permit a flash of light of merely a fraction of a second.

An additional result of the trigger pull is the actuation of the thud sounder E through the following circuit. It may be traced from the line 85 by the line 135, 136, 129, across the switch 106c, back by 130 to 131, 110, 111, 104, 103, thence across to 93 at the intersection point 93a.

Thus, at each trigger pull, the shot counter bar 98 is advanced one step, the light 83 is flashed on and then off, and the thud sounder E is actuated.

Note that the switch member 106b is actuated at each trigger pull, but performs no function until the last shot is fired. The result of the firing of the last shot is to open the switch 103. At that time the power from the rectifier C, the switch 103 being opened, is shunted from the line 139, 131, and thence along the line 140 across the switch member 106b and back along the line 141 to the junction 92 with the line 93. In addition, the circuit of the light 76 is shunted across the switch 106b.

G indicates a service switch shunted across from 85 to 88 as by the line 142. It is not used in the normal employment of the device.

I will consider now the portion of the wiring diagram, shown in Figure 3, which relates to the cabinet 1. The light source 76 in the gun stand, shown in Figure 2, may be considered to direct a beam of light 150 toward the photocell 77. It will be understood that visual light may be employed for this purpose, light within the range to which the human eye is sensitive, or ultra-violet light, or infra-red light, or any suitable band of radiation. A radio beam may be employed. In any event, the member 77 will be understood to be responsive to whatever light or radiation is emitted or directed from the source 76 so that, when the source 76 is energized in response to the operation of the coin controlled switch 73, the sensitive member 77 is effective to energize or to start the operation

of the mechanism within the cabinet 1, without the necessity of any conductive connection between the gun and gun stand and the cabinet 1 and the target mechanism housed therein.

Referring in detail to Figure 3, H indicates a photo-electric amplifier which receives its power from an outside source of any suitable nature, for example 110 volt alternating current. The circuit may be indicated as including the lines 151 and 152, including the manually controlled cut-off switch 153. Assuming that the photoelectric amplifier H is ready for operation, with the switch 153 closed, the impingement of the beam 150 against the sensitive member 77 causes a flow of current through the lines 154 and 155 and the electro-magnet 156 which closes the switch 157 normally held open as by the spring 158.

In other words, the result of the insertion of a coin in the cabinet 70 and the closure of the switch member 73 is to close the switch 157 with the following results. A circuit is closed from the main line 151 by the line 159 through the motor 63, thence by the line 160 to the contact point 161 across the switch 157 and back by the line 162 to the main line 152. Thus the motor is put into operation and the pendulum structure earlier described, including the pendulum member 59 and the photo cell 60, begins to swing through its predetermined arc.

A circuit is also closed from the line 151 to the primary coil of the transformer J and thence along the line 163 to the contact 161 and back by the line 162 to the main line 152. This provides current, from the secondary coil of the transformer J, for the reset magnet 31 by a circuit which includes the line 164, switch 165, contact 166 and line 167. The result of such energization is to move the detent 28 into released position and to permit the reset bar 15 to move in response to the spring 18, from the dotted line to the full line position of Figure 3, which moves the indicator arm 10 to initial position.

In order to release the detent 28, so that it will be in position for score counter service, I provide the slow-acting magnet 168 connected in parallel as by the lines 169 and 170 with the secondary coil of the transformer J. Thus the switch 165 is automatically broken after a predetermined interval, permitting the detent 28 to drop back into position. The magnet 168 may be set to release after a time sufficient to allow the bar 15 to return to its initial position.

Assume that the device is now in play and that the operator aims the rifle 80 properly and makes a hit against the photo cell 60. The result is to close a circuit through the lines 58 and 59, the moving contacts 54 and 55, the fixed arcuate contacts 56 and 57, and the lines 171 and 171a with the photoelectric amplifier K. The amplifier receives its energy from the main lines 151, 152 as by the lines 172 and 173. 174 indicates an electric relay adapted to control the switch 175 in response to energy from the photoelectric amplifier flowing through the lines 176, 177.

The result of a hit, and energization of the cell 60, is thus the closure of the switch 175. The result of such a closure or hit is a flow of current from the line 151 along 178 to the solenoid coil 23 and back along 179 across the switch 175 to the line 180 back across the switch 157 and the line 162 to the opposite main line 152. The result of this flow of energy is to move the

solenoid member 24 in such fashion as to move the bar 15 one step to the right, through its engagement by the dog 27. Thus the indicator finger 10 is moved one step. Each time that a hit is recorded the bar 15 is moved an additional step and if a completely successful score is shot, the bar is moved far enough to cause the contacts 44 to close the switch 45 against the fixed contact 46. This permits a flow of energy along the line 178, 181 to the primary coil of the transformer 47 and thence by the line 181a to the contact 46, switch 45 and back by 182 to the opposite main line 152. The energization of the primary of the transformer 47 causes a flow of current along the line 183 through the solenoid 43 and back by 184 to the secondary coil.

The energization of the solenoid 43 through the mechanism earlier described moves the bird 35 into the open, through the opened doors 7 and 8. At the last shot, the mechanism earlier described cuts off further operation of the device as the beam 150 is interrupted. However, the bird stays in indicating position until another coin is inserted and the above described sequence begins again.

M is a service switch shunted across the lines 163 and 152 to manually energize the motor 63 and the transformer J associated with the reset electro-magnet 31. It is not used in the normal employment of the device.

It will be realized whereas I herein show and describe a practical operative device, nevertheless many changes might be made in the size, shape, number and disposition of the parts without departing materially from the spirit of my invention, and I wish, therefore, that my showing be taken as in a large sense diagrammatic or illustrative.

It will be understood for example that whereas I have described and shown a photoelectric cell mounted on the pendulum and a member 17, sensitive to radiation, mounted on the target base, I wish my description and claims to be interpreted with sufficient breadth to include the employment of reflecting means for directing radiation from the light source or source of radiation. For example, in the place of mounting a photo cell 60 upon the pendulum, I might employ any suitable reflecting means on the pendulum whereby light from the gun lamp 83 is directly or indirectly reflected upon a photo cell which need not move with the pendulum. Similarly, any suitable reflecting means may be employed for directing reflected light or radiant energy from the source 76 to the sensitive member 17.

I claim:

1. In an electric target range, a target base, a target mounted thereon, said target including a movable portion and means for moving it, a firing stand, a coin controlled switch in said firing stand, a source of radiant energy associated with said stand, means for energizing said source of radiant energy in response to the actuation of said coin controlled switch, a member, associated with said target base, adapted to respond to the emission of radiant energy from said source, and an actuating connection between said responsive member and said target mechanism effective to set said movable portion in operation.

2. In an electric target range, a target base, a target mounted thereon, including photosensitive means, a firing stand, a coin controlled switch in said firing stand, a source of radiant energy associated with said firing stand, means for energizing said source of radiant energy in response to the actuation of said coin controlled switch, a member associated with said target base adapted to respond to the emission of radiant energy from said source, a target circuit associated with said base, including a switch, means for closing said switch in response to excitement of said member, and aimable means for directing flashes of light at said target. 5

3. In an electric target range, a target base 15 and a photosensitive target thereon, a gun stand base, and an actuating connection between the target base and the gun stand base, including a source of light on the gun stand base and a light sensitive element other than the target 20 element on the target base, a coin operated switch on the gun stand base, and means for illuminating said light source in response to actuation of said coin operated switch, and target moving means responsive to the actuation of said 25 last mentioned light sensitive element.

4. In a target adapted for use with guns shooting a flash of light, a base, a pendulum mounted on said base and means for actuating it, a photosensitive member mounted on and swinging 30 with said pendulum, a face in the form of a clock face and having a plurality of symbols arranged thereabout to indicate hits, a hand normally fixed but movable about said clock face, and means for moving said hand one step in response to each impingement of a flash of light upon said photosensitive member. 35

5. In a target adapted for use with guns shooting a flash of light, a base, a pendulum mounted on said base and means for actuating 40 it, a photosensitive member mounted on and swinging with said pendulum, a face in the form of a clock face and having a plurality of symbols arranged thereabout to indicate hits, a hand normally fixed but movable about said clock 45 face, means for moving said hand one step in response to each impingement of a flash of light upon said photosensitive member, and an additional indicator member and means for actuating it when the hand is passed entirely around 50 the clock face and across all of the symbols surrounding said face.

6. In an electric target range, a target base, a target mounted thereon, including photosensitive means, a target circuit on said target base, 55 a conductive connection between said target circuit and a source of commercial electric current, a firing stand and a firing stand circuit, a coin control switch in said firing stand circuit, a separate conductive connection between said firing stand circuit and a source of commercial electric current, a source of radiant energy associated with said firing stand, a member associated with said target base adapted to respond to the emission of radiant energy from said source, switch means in said target circuit, means for closing said switch means in response to the excitement of said member, and aimable means for directing a flash of light at said target. 65
